COMBINATION CURTAIN AND SHADE HOLDER

Louis Farmer and Leo Ricci, New Kensington, Pa.

Application July 22, 1936, Serial No. 92,002

4 Claims. (Cl. 248—255)

This invention relates to curtain supports and more particularly to the brackets adapted to be mounted upon the window frame for supporting the window shade as well as the window curtains, 5 and drapes when desired.

One of the objects of the present invention is to provide a curtain support of the above general character having relatively few parts which may be inexpensively manufactured.

A further object is to provide a support of the above character, which will be strong and durable in construction and which may be easily and quickly mounted upon the window frame.

A further object is to provide a curtain support 15 with an attachment whereby drapes may be suspended from the same support when desired.

A further object is to provide a combined curtain, shade and drape support in which the parts interfit to permit easy and quick assembly or disassembly, and which will be free from lost motion or looseness when the parts are assembled.

A further object is to provide a support of the last above-mentioned character, in which the parts coact with the frame and with each other 25 to support the curtain, shade and drapes in a substantial manner.

A further object is to provide a device of the last above-mentioned character, in which the parts may be mounted and assembled or disassembled without special tools other than an ordinary screw driver.

Other objects will be in part obvious from the annexed drawing and in part hereinafter indicated in connection with the following analysis 35 of this invention.

This invention accordingly consists in the features of construction, combination of parts, and in the unique relation of the members and in the relative proportioning and disposition thereof, all as more completely outlined herein.

To enable others skilled in the art fully to comprehend the underlying features of this invention, that they may embody the same by the numerous modifications in structure and relation 45 contemplated by the invention, a drawing depicting a preferred form of the invention has been annexed as a part of this disclosure, in which:

Fig. 1 is a plan view, partly in section, or broken away, showing the complete assembly;

Fig. 2 is an elevational view, partly in section of the same;

Fig. 3 is a detail perspective view of one of the supports in disassembled relation.

Referring now to the drawing in detail, 10 indicates a portion of the window frame such as

the top or the side panels, to which the curtain support is adapted to be attached. As herein illustrated the window shade 11 is of usual or standard construction, that is, comprising a roller upon which the shade is mounted to be wound, the roller having the usual end pins 12 adapted to coact with recesses 13 in the supports. It is to be understood, in describing the invention, that the shade and curtain supports must be made in usual "rights and lefts", but for simplicity 10 only one of these supports will be described in detail (see Fig. 3), the other being the mere reverse, and the recess 13 being the usual perforation in one support and the slot in the other as is common to standard constructions. The term 15 "recess" as herein used is applicable to either of these types of openings.

This recess 13 is mounted in the part 14 of the supporting bracket, which is stamped preferably from sheet metal in any well known manner and is provided at what may be termed its inner end with two laterally extending lugs 15, each provided with an opening 16 adapted to receive the screws 17, all in a well known manner.

Extending oppositely from these lugs 15 and in the same plane is a relatively short portion 18 adapted to abut against the window frame 10. This part 18 has directly connected therewith a right-angle portion 20 extending parallel to the part 14 and for a material distance outwardly from the plane of the window frame 10. This part 20 is adapted to coact with the well known telescopic curtain rod indicated at 21, this rod as shown being what might be termed C-shaped in cross-section and is adapted to slip over the projection 20 until its end coacts with the right-angle portion 18, that is, when the device is used merely for supporting the window shade and curtain. It is of course to be understood that the projection 20 is of a size to fit snugly within the C-shaped end of the curtain rod 20 when that type is used whereby the latter is held in position by frictional engagement.

It will be noted that the part 20 has a vertically extending slot 22 cut downwardly about 45 half the width of the member 20. This is for the purpose of coacting with the drape attachment which comprises a portion 23 substantially coextensive with the part 20 and adapted to occupy a position parallel thereto and slightly 50 spaced therefrom. This part 23 is adapted to co-operate with the drape curtain rod indicated at 24 which, like the part 21, may be of standard construction, substantially C-shaped in cross-section. Thus the drape rod 24 may be slipped over 55

the part 23 snugly, as shown in Fig. 1, thereby to form a frictional cooperation therewith.

Extending at right angles to the part 23 is a portion 25, the end of which is then bent at right angles to provide an abutment 26, and the lower part of the portion 25 is slotted upwardly about half way, as indicated at 27. It will be noted particularly that the distance indicated by the arrows 28 (Fig. 3) is equal to the distance 10 between the parts 20 and 14 of the main support (arrow 29) in Fig. 1, and the length of the abutment 26 is equal to the distance between the surface 18 and the slot 22 (Fig. 3). Thus when the parts are assembled the slot 27 co-operates 15 with the slot 22 (Fig. 3) and permits the drape bracket to be positioned with the abutment 26 in close engagement and parallel to the surface 14. The edge of the abutment 26 engages the angle between the surfaces 18 and 14 (Fig. 1). 20 Thus there is a three line or surface contact between the drape attachment and the main supporting bracket providing a substantial connection, free from looseness or vibration.

The method of use or operation of the device 25 is of course obvious to those familiar with the subject. It may be stated, however, that the right and left bracket members proper are secured to opposite sides of the window merely by the insertion of screws 17 through the holes 16 30 in the bent-over lugs 15, as shown. The roller shade 11 may then be inserted into the recesses or openings 13. When curtains alone are desired, these are placed upon the curtain rod 21 in the usual well known manner and such end of the rod 21 is slipped over the respective projections 35 20 at opposite sides of the window, the end of the rod 21 abutting the surface 18, thus making a strong substantially frictional fit. If, however, drapes are to be added, then the curtain rods 21 are withdrawn from their supports or projections 40 20 out of contact with the surface 18, or approximately one-half inch, and the attachment 23 is slipped into place by bringing the recesses 22 and 27 into registry. The curtain rod 21 is then forced back upon the projections 20 until the ends engage the surfaces 25 of the attachment. The drapes are then positioned upon the drape rod 24, the ends of which are forced over the 45 projections 23. The entire assembly is then complete and forms a strong substantial support 50 for the shade, curtain and drapes.

It will be noted particularly that the bent-over ends of the C-shaped curtain rod 21 are so positioned with relation to the pin 12 (Fig. 1) of the shade roller as to prevent accidental removal of 55 the curtain roller. This has a particular advantage for it frequently happens that the shade suddenly and unexpectedly rolls up, causing the shade roller to "bounce" out of the slotted recess 13 on one of the brackets. Such accidents are 60 eliminated by means of the present construction when the parts are properly proportioned, positioned and assembled.

The entire device is of simple and practical 65 construction which may be very inexpensively manufactured. It has a neat, ornamental appearance, free from unsightly external projections when it is desired to use merely the shade and curtain support. The drape attachment may be purchased separately, if and when desired, and 70 when not in use for any reason may be removed and kept in a safe place until needed.

The present arrangement does away with alternatives heretofore required when it was desired 75 to shift from shade and curtain to shade, cur-

tain and drape support, the shade and curtain features always being present yet not in an objectionable or unsightly way.

It is thus seen that the present invention is well adapted to accomplish, among other objects, all of the objects and advantages herein set forth. 5

Without further analysis the foregoing will so fully reveal the gist of this invention that others can, by applying current knowledge, readily adapt 10 it for various applications without omitting certain features that, from the standpoint of the prior art, fairly constitute essential characteristics of the generic or specific aspects of this invention, and therefore such adaptations should 15 and are intended to be comprehended within the meaning and range of equivalency of the following claims.

We claim:—

1. A combination support of the character described comprising a relatively flat member provided with a recess adapted to receive the end of a roller curtain and having at its inner end laterally extending securing means to permit attachment to a window frame, said member also having a portion lying in the same plane as said securing means and provided with a projection extending substantially parallel to and closely adjacent said flat member adapted to receive the end of a curtain rod, said projection having a vertically disposed slot spaced from the laterally extending portion, and an attachment of generally L-shaped construction having a slot in one portion adapted to coact with said first-mentioned slot, the other portion constituting 35 a projection normally extending parallel to said first-mentioned projection.

2. A combination support of the character described comprising a relatively flat member provided with a recess adapted to receive the end 40 of a roller curtain and having at its inner end laterally extending securing means to permit attachment to a window frame, said member also having a portion lying in the same plane as said securing means and provided with a projection extending substantially parallel to and closely adjacent said flat member adapted to receive the end of a curtain rod, said last-named portion having a vertically disposed slot spaced from the laterally extending portion, and an attachment of generally L-shaped construction 45 having a slot in one portion adapted to coact with said first-mentioned slot, another portion constituting a projection normally extending parallel to said first-mentioned projection, said slotted portion of said attachment having an abutment at right angles thereto adapted to coact with said relatively flat member when the parts are assembled. 50

3. A combination support of the character described comprising a body portion having laterally extending attaching means permitting the support to be mounted on a window frame and an opposite laterally extending portion lying in the plane of the attaching means and adapted to 60 coact with the surface of the window frame, and a projection extending from said last portion in a direction substantially parallel to the body portion, said projection having a vertically extending slot spaced from the adjacent portion, and an attachment having a complementary slot in one part adapted to coact with the first-mentioned slot, another part constituting a projection adapted to receive a curtain rod being positioned 65 parallel to but spaced from the body portion. 70

said part provided with a slot also having a right-angle abutment, the surface of which is adapted to coact with the surface of the body portion.

4. A combination support of the character described comprising a body portion having laterally extending attaching means permitting the support to be mounted on a window frame and an opposite laterally extending portion lying in the plane of the attaching means and adapted 10 to coact with the surface of the window frame, and a projection extending from said last portion in a direction substantially parallel to the body portion, said projection having a vertically

extending slot spaced from the adjacent portion, and an attachment having a complementary slot in one part adapted to coact with the first-mentioned slot, another part constituting a projection adapted to receive a curtain rod being positioned parallel to but spaced from the body portion, said part provided with a slot also having a right-angle abutment, the surface of which is adapted to coact with the surface of the body portion, and the end of the abutment engaging 10 the surface of said laterally extending portion.
